UNITED STATES PATENT OFFICE.

FRANK W. BEBERDICK, OF WEST HOBOKEN, NEW JERSEY.

DESIGN FOR A COAT-PATTERN.

SPECIFICATION forming part of Design No. 30,215, dated February 14, 1899.

Application filed November 8, 1898. Serial No. 695,900. Term of patent 14 years.

To all whom it may concern:

Be it known that I, FRANK W. BEBERDICK, a citizen of the United States, residing at West Hoboken, in the county of Hudson and State of New Jersey, have invented and produced a new and original Design for a Coat-Pattern, of which the following is a specification, reference being had to the accompanying drawing, forming part thereof.

10 The drawing represents in plan view a pattern of one side and half of the back of the coat, showing my new design, and it will be understood that the other side and half of the back are the same.

15 As shown in the drawing, the leading or material feature of my design consists in the part A, forming one side and half the front, and the part B, forming half of the back, and in the particular shape or contour given to 20 the upper edge or ends of these parts. From the point a^2 the edge of the part A extends outwardly and downwardly in a full curve to the point a' , from which point the edge of the part A extends downward in a vertical straight line to the point a . From the point a the edge of the part A extends in a straight horizontal line, forming the bottom of the part A. From the point a^2 the edge of the part A extends downwardly in a sharply-inclined straight 25 line to the point a^3 , which deviates but slightly from the vertical, forming, with the curved line $a^2 a'$, a sharp upwardly-projecting portion. From the point a^3 the edge of the part A is curved inwardly and upwardly to the 30 point a^5 , forming the curved line a^4 , constituting a part of the neck-opening. The point a^5 is on substantially the same horizontal plane as the point a^2 . From the point a^5 the edge of the part A extends in a slight downward 35 then upward curve to the point a^7 , forming the compound-curved line a^6 . The point a^7 is located below the point a^5 and slightly above the point a^3 . The compound-curved line a^6 represents the shoulder line or seam.

40 The edge of the upper portion of the part A extends downwardly and inwardly from the point a^7 in a curve deviating only slightly from a straight line to the point C^2 , from which

point the said edge is curved in a small semi-circle to the point C^3 . From the point C^3 the 50 edge extends downwardly and is slightly curved outwardly and then inwardly to the point C^4 , from which point the said edge extends downwardly in a straight line to the bottom of the garment.

55 The outer edge of the part B extends in a straight line b^5 from its extreme upper point b^4 to the extreme lower point b^6 . The inner edge of the part B extends in a straight line from the bottom thereof to the point C^4 , coinciding with the part A. From the point C^4 the edge of the part B extends upwardly and is slightly curved outwardly and then inwardly until it meets the point C^3 of the part A at the point b^8 , thus forming a double-curved opening b^7 , tapering to a meeting-point at the upper and lower ends thereof. From the point b^8 the edge of the part B extends upwardly, curving first upwardly and then extending in an inclined substantially 70 straight line to the point b , which is opposite, but slightly below, the point a^7 of the part A and separated therefrom by a narrow space b^9 . From the point b the edge of the part B extends upwardly in a straight but sharply-75 inclined line to the point b^2 , thus giving the shape of an obtuse angle to the point b . The upper edge of the part B extends from the point b^2 in a downward curve to the point b^4 , which point is located slightly below the point b^2 , but on the same horizontal plane as the point a^5 of the part A.

80 Having fully described my invention, I claim as new and desire to secure by Letters Patent—

85 The design for a coat-pattern as herein shown and described.

In testimony that I claim the foregoing as my invention I have signed my name, in presence of the subscribing witnesses, this 29th 90 day of October, 1898.

FRANK W. BEBERDICK.
